UNITED STATES PATENT OFFICE.

JOHN SAMUELS, OF ROCK SLOPE, ALABAMA, ASSIGNOR, BY MESNE ASSIGNMENTS, TO JOHN SAMUELS, EUGENE THOMASON, W. C. LONG, AND J. E. LACEY, A COPARTNERSHIP.

AUTOMATIC BRAKE MECHANISM FOR TRAINS.

1,112,481.

Specification of Letters Patent.

Patented Oct. 6, 1914.

Application filed October 25, 1913. Serial No. 797,260.

To all whom it may concern:

Be it known that I, JOHN SAMUELS, a citizen of the United States of America, residing at Rock Slope, in the county of Jefferson and State of Alabama, have invented certain new and useful Improvements in Automatic Brake Mechanism for Trains, of which the following is a specification.

- 10 My invention relates to an electrically controlled mechanism, which will operate automatically, in connection with any standard type of block signal, when a train runs into a block without license, to apply the brakes on such train, close the engine throttle, and explode one or more torpedoes located at any desired points on the train, as, for instance, over the cab, caboose, or at any other desired point.
- 20 One object of my invention is to make certain the automatic application of the brakes, and, to this end, I provide several independent devices which will act as bleeders to lower the pressure in the train line system sufficiently to apply the brakes.
- 25 One device comprises an electrically controlled valve, which, when operated, opens the train line pressure to a bleeder port and also shunts the train line pressure to an air cylinder connected to and adapted to operate the throttle.

30 A further object is to supplement the safety appliances by the use of torpedoes, arranged to be exploded electrically when the train runs past a danger signal. These torpedoes are adapted to explode glass tubes, which are connected to the train line system and, when exploded, serve as bleeders to insure the application of the brakes, in 35 the event that the valve or throttle control mechanism should fail to operate.

40 My invention further comprises means whereby the engine can be cut out from under the control of the automatic circuits when desired, as in the case of switching, or under other conditions, making it necessary to operate past a semaphore.

45 My invention further comprises the details of construction and arrangements of parts which, in their preferred embodiment are more particularly described and claimed hereinafter, reference being made to the accompanying drawings in which—

50 Figure 1 illustrates the track circuits in elevation and the automatic train circuits

diagrammatically. Fig. 2 is a side elevation of a locomotive equipped with the electrical appliances for automatically carrying into effect the objects hereinbefore stated. Fig. 3 is a diagrammatic detail illustration showing the electrical and air pipe connections on the locomotive. Fig. 4 is a detail view of the torpedoes and over-head bleeders. Fig. 5 is a transverse vertical section through the magnetically controlled valve 60 on the train-line. Fig. 6 is a front view of the tell-tale dial connected to the valve shown in Fig. 5. Fig. 7 is a longitudinal vertical section taken on the line $x-x$ of Fig. 6.

70 Similar reference numerals refer to similar parts throughout the drawings.

75 My invention is adapted for use in connection with standard types of block signals. The one which I have chosen for the sake of illustration comprises the standard 1, the semaphore 2 and contacts 3 adapted to be closed by a contact plate 4 on the semaphore only when in raised position indicating danger ahead in the block. The contacts 3 are connected by wires to a suitable battery 5, and each wire leads to a conductor 6, one of which is disposed on each side of the track rails 7. The locomotive 8 carries any suitable means for collecting the current 80 from the conductors 6, that shown comprising contacts 9 disposed on each side of the locomotive and connected by wires 10 and 11, to a magnet 12. This magnet, when energized by the closing of the circuit across 85 the contacts 9, closes a relay switch 13 and closes the automatic wiring circuits on the locomotive to a relay battery 14 carried by the locomotive or train. A wire 15, leads from one side of the battery and branches, 90 one part 16 thereof leading to the electromagnet 17 and to switch 18, and, when the latter is closed, to the switch 13 and back to the battery. The other branch 17^a of the wire, extends overhead and is connected by 95 branch wires 18^a to torpedo or explosive caps 19, the current returning by wire 20 across switches 18 and 13 to the battery.

100 The magnet 17 controls a core 21, which, at its outer end is pivotally connected to a crank 22 that operates a rotary three-way valve 23. This valve is tapered and makes an air-tight turning fit in a three-way valve casing 23^a, which casing, at one side, is connected through the pipe 24 to the train line 110

pipe 25. The casing 23^a has a large port 26 which communicates with a pipe 27 that leads to an air cylinder 28, having a piston 29, to the free end of which is pivoted a link 30. This link is connected by a pivot pin 31, disposed at its outer end, to an extension 33 on the rocking hand grip member 34, which member controls the ratchet lock for the throttle. The throttle lever, when pulled by the link 30 and piston 29, acts through ordinary operating connections to close the throttle valve 35, and the piston will be operated to cut off steam when the air pressure is admitted to cylinder 28 by the turning of valve 23, so that its ports establish communication between the pipes 24 and 27. The valve 23 has a bleeder port 36 which connects with a contracted bleeder port 27 in the valve casing and acts to gradually reduce the pressure in the train line and in the cylinder 28, when the valve 23 is moved to apply the brakes.

The valve casing 23^a, at its outer end, is provided with an integral extension casing 38 having its outer end closed by a glass 39, held in place by a fixed lock ring or cap 40, that is riveted to the end of extension 38. The valve, at the center of its inner end, has a rounded stud 41, adapted to pass through a central opening in the inner wall of the casing 38. On the outer end of the stud is fixedly mounted an arm 42, which carries a pivoted inturned spring-pressed dog 43, which dog engages a ratchet wheel 44, carrying a pointer arm 45. This arm moves over a dial 46 having marked thereon a series of numbers progressing from 1 to 10 and being spaced so that each automatic operation of valve 23 will, through the connections described, cause the pointer to be advanced over the dial to indicate the next higher number to the one last pointed to. The dog will travel back freely over the ratchet wheel while the valve is reset to a closed position, without disturbing the position of the pointer, and since cap 40 is not removable, the pointer serves as a tell-tale which will indicate each time the engineer has disobeyed orders, and, as a result, the automatic apparatus has been called upon to stop the train.

Branch pipe 47 is connected with the train line pipe 25, and extends upwardly to the top of the cab, caboose or car, where a branch pipe 48 leads from it, the ends of both pipes 47 and 48 being connected each to an elbow 49 which is provided with a bleeder port. A gage glass 50, closed at its outer end, is connected by an air tight joint 55 with each elbow 49 to cover and normally close its bleeder port. The other end of each gage glass is supported by an angle iron 51, secured to the roof of the cab. Each gage glass is disposed close to the roof of the cab, and between the roof and the glass

is interposed an explosive torpedo 19. Each torpedo and glass is protected by a cap or cover 52, detachably connected to the roof of the cab.

In operation, when one train has passed into a block, the semaphore 2, which it passed, is raised, and the circuits from battery 5 are closed to the contacts 6. If another train attempts to enter the block before the first train has cleared it, the brushes 9 on the train entering the block will take current from the contacts 6 and energize the relay magnet 12, thereby closing the switch 13 and causing current from the battery 14 to flow to the magnet 17, which will, through the connections described, move valve 23 to admit the train line pressure to pipe 27 and to the bleeder port 37. The air pressure will flow to the cylinder 28, and in the manner described, will close the throttle and shut off steam from the locomotive. At the same time the current flowing through circuits 17^a, 18^a and 20 will explode the torpedoes 19, giving an alarm signal to the engineer, and at the same time breaking the gage glasses 50, so that the train line pressure is bled also through the pipes 47 and 48, and the brakes applied to stop the train. These several bleeders, either separately or jointly, make certain the ultimate application of the brakes even if for any reason the throttle closing mechanism should fail to operate, but the bleeders are designed not to exhaust the air and lower the air pressure sufficiently to interfere with the reliable operation of the air motor 28 responsive to the inrush of air in the opening of the valve 23. If, for any reason, it is not desired to have the automatic circuits operate, the engineer opens a switch 18. For each time the valve 23 is operated, the tell-tale pointer 42 is advanced over the dial, and furnishes conclusive evidence of neglect or carelessness on the part of the engineer.

Only one gage glass is necessary, though I prefer to use two. The arrangement of the glasses and torpedoes may be varied to suit the convenience of the user. If desired, the relay battery can be dispensed with and battery 5 relied upon to deliver sufficient current to perform the automatic operations described. I prefer to use the different automatic safe guards described in the combination, as each supplements and makes certain the effective operation of the whole safety appliance.

When valve 23 is operated to deliver air pressure to the cylinder 28, the valve port 36 will register with the bleeder port 37 and the latter will exhaust the pressure from the cylinder 28 so that the throttle is released for manual control. The bleeder port 37 would in time drop the pressure sufficiently in the train line 25 to apply the

brakes, but this automatic application of the brakes is made more rapid and reliable by the fracture of one or more of the gage glasses 50.

5. What I claim as new, and desire to secure Letters Patent is:—

1. Means for automatically arresting a train, said means comprising, in combination with the air brake system, an air motor, a pipe connecting said motor with the air brake system, a valve in said pipe for controlling the flow of air to said motor, means to automatically operate said valve, means controlled by said valve both to admit and slowly exhaust the air pressure from said motor, and means controlled by said motor to stop the train, substantially as described.

2. In an apparatus of the character described, in combination with a locomotive and air brake system, a pipe leading from the air brake system, a two-way valve to control the exhaust of air through said pipe, means to automatically operate said valve under predetermined conditions, a main exhaust pipe and a bleeder pipe controlled by said valve and simultaneously opened or closed thereby, and mechanism actuated by the exhaust air passing through the main exhaust pipe for shutting off the motor fluid to the locomotive.

3. In combination, a train, its air brake system, a normally closed pipe line con-

nected with the air brake system and having a plurality of bleeder ports therein, a valve means in said pipe line for controlling one or more of said ports, and one or more gage glasses included in said pipe line and normally closing the other of said bleeder ports, an explosive device adjacent to each gage glass, electrically controlled means operable automatically under predetermined conditions for exploding said device or devices and for operating said valve means to open said ports, and track means for energizing said electrical means on a passing train, substantially as described.

4. Means for automatically arresting a train, said means comprising in combination with the air brake system, an air motor, a pipe connecting said motor with the air brake system, an indicating valve in said pipe for controlling the flow of air to said motor, means to automatically operate said valve, means controlled by said valve both to admit and slowly exhaust the air pressure from said motor, and means controlled by said motor to stop the train, substantially as described.

In testimony whereof I affix my signature in presence of two witnesses.

JOHN SAMUELS.
